UNITED STATES PATENT OFFICE.

FRITZ PECHSTEIN, OF WILMERSDORF-BERLIN, GERMANY, ASSIGNOR TO C. A. FESCA & SOHN, OF BERLIN-LICHTENBERG, GERMANY, A FIRM.

CENTRIFUGE.

1,381,330.

Specification of Letters Patent. Patented June 14, 1921.

Application filed December 18, 1919. Serial No. 345,664.

To all whom it may concern:

Be it known that I, FRITZ PECHSTEIN, a citizen of Germany, and residing at Wilmersdorf-Berlin, Germany, have invented 5 certain new and useful Improvements in Centrifuges, of which the following is a specification.

This invention relates to continuously acting centrifuges for pulps and it has for its 10 object to provide a charging device therefor by which the material to be acted upon shall be fed into the centrifugal drum in definite quantities and at definite periods.

Centrifugal machines embodying automatic means for controlling both the feed thereto and the discharge therefrom are, generally speaking, known in the art. The present invention comprises however a particular construction, having a separate funnel 15 above the drum of the centrifugal machine, which permits the feeding into the drum out of a large tank or other reservoir.

The accompanying drawing shows the invention as applied to a centrifuge of the 20 kind in which the centrifugal drum can be pressed against a rotatable part of the stationary drum casing. This embodiment of the invention is represented in a sectional elevation, the charging device being, for the 25 sake of illustration, assumed to be set at an angle of 90° to the centrifugal machine.

In a footstep bearing 1 a shaft 2 can rotate that carries the centrifugal drum 3 at its upper end. To the lower end of the 30 bearing 1 a roller 5 is fitted to bear on a cam 4. On each rotation of the cam 4 the roller 5 will enter the recess 6 thereof so as to lower the shaft 2 and thus move the upper edge 7 of the drum 3 away from a 35 plate 8 fixed to a tubular duct 8'. This duct is mounted by means of a ball bearing 8'' in a fixedly disposed cover 9 of the drum casing. By so lowering the drum shaft an annular slot is formed between a 40 edge 7 of the drum 3 and the plate 8. Through such slot or clearance the contents of the drum are discharged therefrom owing to the continually acting centrifugal force. The recess 6 having passed the roller 45 5, the drum is raised again by the circular portion of the cam 4 and the slot thus closed. Immediately after the contents of the drum have left it and the drum has become pressed against the plate 8, the drum

is recharged by the device hereafter described.

Disposed above the centrifugal drum 3 and coaxial therewith is a funnel 10 fitted with slides 11 and 12. These are operated by either raising or lowering a rod 15 provided with a rack 13 at its upper end. The rod 15 is adapted to slide in guides 14. The lower end of the rod 15 is connected by a link 16 with a double-armed lever 18 fulcrumed at 17. This lever carries a roller 20 that bears on a cam 19. The rack 13 is in gear with a toothed wheel 22 keyed on an axle 21. The sliding motion of the rod 15 will thus cause the axle 21 to rotate together with a toothed wheel 23 keyed thereon to gear with a rack 24 fitted to the slide 11 so that the latter shall be moved by the axle 21 rotating.

The slide 12, designed to control the inlet 25 of the funnel 10, is a rotary one, carried on an arm 28 fixed to an axle 26. To one of the ends of the axle 26 a lever 28' is secured which is provided with a roller 27.

Whenever the slide 11, which is for the outlet 29 of the funnel 10, is open, the roller 27 is resting in a horizontal groove 30 of the slide 11. The slide 12 then is maintained in the position shown. When, however, the slide 11 is moved so as to close the outlet 29 the roller 27 will enter a downward extension 31 of the groove 30 and thereby cause the slide to be rotated so as to uncover the inlet 25.

In this way, whenever the inlet 25 is open the outlet 29 will be covered, and vice versa. 90 The opening motion of the slide 11 takes place suddenly, *i.e.* the moment the roller 20 of the lever 18 enters the recess 19' of the cam 19. The closing motion of the slide 11, however, is accomplished gradually and 95 has been finished as soon as the roller 20 has left the recess 19' of cam 19.

The cam 4, serving to raise and lower the centrifugal drum 3, and the cam 19 designed to govern the charging device described, are mounted on the same arbor 32 and are so relatively disposed that charging and discharging shall be exactly timed for a due automatic working of the centrifuge.

I claim:

1. In a centrifuge, the combination of a centrifugal drum with a funnel above the latter, a slide controlling the inlet of such

funnel, a slide controlling the outlet thereof, means for operating these slides so as to cover the outlet while uncovering the inlet, and vice versa, and means for automatically discharging the contents of the said drum, substantially as set forth.

2. In a centrifuge, the combination of a centrifugal drum with a funnel above the latter, a slide controlling the inlet of such 10 funnel, a slide controlling the outlet thereof, means for operating these slides so as to cover the outlet while uncovering the inlet, and vice versa, a duct between the outlet of this funnel and the said centrifugal 15 drum, means carrying such duct rotatably, a plate fixed to this duct to bear upon the upper edge of the said centrifugal drum and means for vertically displacing the latter, substantially as set forth.
- 20 3. In a centrifuge, the combination of a centrifugal drum with a funnel above the latter, a rotary slide controlling the inlet of such funnel, a slide controlling the outlet thereof, a groove in the latter slide, and 25 an arm rigid with the said rotary slide, such arm engaging in said groove, substantially as set forth.

4. In a centrifuge, the combination of a centrifugal drum with a funnel above the

latter, a rotary slide controlling the inlet 30 of such funnel, a slide controlling the outlet thereof, a groove in the latter slide, an arm rigid with the said rotary slide, such arm engaging in said groove, a cam, and a gearing connecting such cam to the said outlet 35 slide, substantially as set forth.

5. In a centrifuge, the combination of a centrifugal drum with a funnel above the latter, a slide controlling the inlet of such 40 funnel, a slide controlling the outlet thereof, means for operating these slides so as to cover the outlet while uncovering the inlet, and vice versa, a duct between the outlet of this funnel and the said centrifugal drum, means carrying such duct rotatably, a plate 45 fixed to this duct to bear upon the upper edge of the said centrifugal drum, a cam for vertically displacing the latter, a cam coaxial with the first said cam, and a gearing connecting the second said cam to the 50 said outlet slide, substantially as set forth.

In testimony whereof, I affix my signature in the presence of two witnesses.

FRITZ PECHSTEIN.
